United States Patent Office

Des. 230,293
Patented Feb. 5, 1974

230,293

PUTTER

Rudolph A. Gall, 7800 Webster Road,
Middleburg Heights, Ohio 44130

Filed June 22, 1972, Ser. No. 265,187

Term of patent 14 years

The portion of the term of the patent subsequent to
Feb. 5, 1988, has been disclaimed

Int. Cl. D21—02

U.S. Cl. D34—5 GC

FIG. 3

FIG. 2

FIG. 1

FIG. 1 is a rear elevation of my new putter design;
 FIG. 2 is a left side elevation of my new putter design;
 FIG. 3 is a top plan view taken from directly above the
 putter head;

FIG. 4 is a front elevation of my new putter design;
 FIG. 5 is a right side elevation of my new putter design;
 and

FIG. 6 is a bottom plan view taken looking directly
 onto the putter head.

I claim:

The ornamental design of a putter, substantially as
 shown and described.
